ELECTRICAL CONTACT DEVICE HAVING A SPRING ACTING AGAINST A PLATE FOR MOVING A PLURALITY OF CONTACT ELEMENTS

Winfield B. Blank, Jr., Tulsa, Okla., assignor to Sinclair Research, Inc., New York, N.Y., a corporation of Delaware

Filed Sept. 30, 1963, Ser. No. 312,452
4 Claims. (Cl. 324—62)

This invention is an apparatus for use in a well casing or other pipe to establish an electrical contact within the pipe. The device of this invention is useful in, for example, corrosion determinations. In such operations a plurality of contact devices, for example, two of the units, separated by a prearranged distance, for example, by a spacing tube, may be used to find a difference in electrical potential between sets of two areas on the inside of the casing or other pipe.

This invention is an improvement over devices of this type which are known to the art in that it provides sharp contact points which can pierce thin films of oil, corrosion products, etc., within the pipe to establish metal-to-metal contact. The contact points are spring actuated but are protected from wear by being kept in a retracted position during travel through the pipe until the position is reached where their use is desired. The apparatus comprises a support member of a size suitable for fitting within the pipe to be tested and retractable, sharp, contact means, spring actuated to engage the inside wall of the pipe when released from their protected position. The release mechanism is actuated by a change in direction of travel of the support member through the pipe.

In a preferred embodiment, the device employs contact knives, ideally three or more of them, to center the apparatus in the pipe, and has the set of knives arranged in one plane perpendicular to the axis of the pipe. The spring actuation of the contact knives preferably takes place through a pressure plate which contacts all of the knives, transmitting spring pressure evenly to the knives. The pressure plate also serves to conduct current to and from the contact knives, whereby the current may be conducted by the knives in parallel. Often, the knives will pivot from their retracted position to their extended, operable position, mounting lugs being provided on the support for this purpose.

The release mechanism preferably comprises a locking collar for the knives below the pivot points and this collar is provided with a dragging mechanism which contacts the interior wall of the pipe to be contacted with the knives. Thus during the descent or other travel of the apparatus of the invention through the pipe the dragging mechanism serves to hold the collar, which usually is slidably mounted on the support tube, toward the top of the tube, and the collar holds the knives in their retracted position. The dragging mechanism may comprise a series of stiff wire "cat whiskers."

The movement of the apparatus of this invention toward its test destination is generally described in this specification and claims as "downward" while movement back to the starting position is described as "upward," but it will be understood that this invention may be used with horizontally or obliquely positioned pipes, as well as those vertically positioned.

The dragging members are so positioned on the support that they hold the collar "up," protecting the knives, during "downward" travel of the apparatus. When the direction of travel is reversed, the dragging members catch on the pipe wall or at a coupling relief sufficiently to pull the locking collar "down" thereby releasing the knives, and enabling the spring pressure to open them.

2

A slight "lowering" of the mechanism then sets the knives and establishes a good electrical contact.

An important advantage of the apparatus of this invention is the paucity of parts which it employs and the simple, rugged nature of the operative elements. The assembly may be held together by a hollow bolt and nut and the contacting portion of the assembly is electrically insulated from other parts.

The invention will be better understood by reference to the accompanying drawing which is to be considered illustrative only and not limiting.

In the drawing:

FIGURE 1 is a fragmentary cross-sectional view of the device of the invention with the contact points in their protected position suitable for insertion into the pipe, well-casing, etc. and

FIGURE 2 is a fragmentary cross-sectional view of the device in its operative or contacting position.

The apparatus comprises the support means 11, which in the embodiment shown is a cylindrical piece of tubing. This support member may be provided with a tapered lower end 13 to facilitate entry into the pipe to be explored and also, if desired, with a tapered portion 15 at its upper end to facilitate removal from the pipe. The support member may be suspended or otherwise transported through the pipe by means of any sort of wire line, spacing bar, sinking bar, cable, pipe, tubing etc., directly or indirectly attached to the support member, preferably to the upper and/or lower tapered portions 13 and/or 15 which are electrically insulated from the mid-section 18 of the support 11. The electrical insulation of the mid-section may be brought about by any convenient means, for example, the washers 20 and 22 which may be made of any suitable dielectric material such as hard rubber.

20 The upper and lower, preferably tapered, portions of the tube are fastened interiorly to the spiders 25 and 28, respectively, through which pass the hollow bolt 30 which is provided with the hollow head 33. The nut 36 fastens to the threaded end of the bolt 30 to hold the apparatus together. The bolt 30 and nut 36 are electrically insulated by the dielectric sleeve 39 and the upper and lower dielectric washers 42 and 44.

At the upper portion of mid-section 18 the fixed washer 46 and the slidable washer or pressure plate 48 define the spring chamber 50 which contains the spring 52. Fastened to the outside of the mid-section 18 are three or more lugs 55 and next to each lug is a slot 58 which penetrates the tube. Fastened to each lug by means of the pivot 60 is a knife 63 which has an internal portion 66 and an external portion 68, which portion is usually at an angle to the interior portion 66 and which ends in the point 70. The mid-section 18 is provided externally and below the lugs with the locking collar 72 which is slidably mounted on the tube, for example, by means of 50 spring biased detent means, i.e. the ball bearings 75 which are biased by the springs 77 which operate in the spring chambers 80. The spring chambers 80 may conveniently be formed by a circular depression in the wall of an upper portion of mid-section 18.

60 The collar 72 is provided near its lower end with a plurality of dragging means, for example, the piano wire cat whiskers 82. It will be observed that the collar is of a size sufficient to allow clearance for the external portion 68 of each knife 63 between the collar and the tube. 65 The upper portion of the collar 72 may be provided with the shroud 84 which is slotted to provide for entry of the portions 68, and which serves to prevent the apparatus from hanging up on obstructions in the pipe. Preferably the collar is provided with a taper 88 at its lower portion 70 and the mid-section 18 is provided with the projections 90 preferably at its lowermost periphery. These projections may be, for example, merely screws threaded into the

mid-section 18. The knives 63, as well as the detent 80, act as stops for upward travel of the collar, and the friction developed between the interior of the collar and the outwardly spring-biased portions 68 will insure prevention of too great upward travel of the collar 72 when the knives are in the retracted position even if the springs 77 should fail.

An electrical lead 93 is fastened to any portion of the device which is in electrical connection with the points 70, preferably the washer 46. Another electrical lead, 96, may pass through the hollow bolt 30, for example, to another similar apparatus located farther in the pipe 99. The line through the bolt may be insulated, although the insulating sleeve 39 will usually serve to prevent short circuiting.

The operation of the apparatus is fairly apparent from the drawing. During entrance to the pipe or casing the knives are held in a closed position by the locking collar. The drag of the cat whiskers against the wall of the pipe or casing aids in keeping the knives in the inoperative position with the points protected.

After the testing position has been reached, the apparatus is given an upward motion sufficient to pull the tube upwardly inside the collar which is held down by engagement of the cat whiskers with the inside wall of the pipe. The release of the collar enables spring 52 to expand within the spring chamber causing a downward motion of internal knife portions 66 and outward motion of the external portions 68.

After the desired period of electrical contact has expired, the apparatus may be simply pulled from the pipe.

It is thus apparent that the apparatus of this invention provides a simple means by which good electrical contact may be established within a pipe.

It is claimed:

1. A device for establishing electrical contact within a pipe which comprises a tubular support member, a plurality of contact elements movably mounted on said member for movement between a retracted position in which said contact elements lie adjacent said support member and an extended position in which said contact elements extend outwardly of said support member, a plate within said support member resting upon a portion of each of said contact elements and tending to move said contact elements toward said extended position by gravity when the device is in an upright position, a spring within said support member acting against said plate to bias said contact elements toward said extended position, collar means on said support member movable between a first position in which it is adapted to extend over said contact elements and hold them in said retracted position against the bias of said spring and plate and a second position in which said contact elements are free to move to said extended position, and releasable means for holding said collar means in said first position.

2. The device of claim 1 in which said contact elements are knife elements each arranged for pivotal movement in a plane parallel to the axis of the pipe to be contacted.

3. A device for establishing electrical contact within a pipe which comprises a tubular support member, a plurality of contact elements movably mounted on said member for movement between a retracted position in which said contact elements lie adjacent said support member and an extended position in which said contact

elements extend outwardly of said support member, a plate within said support member resting upon a portion of each of said contact elements and tending to move said contact elements toward said extended position by gravity when the device is in an upright position, a spring within said support member acting against said plate to bias said contact elements toward said extended position, collar means on said support member movable between a first position in which it is adapted to extend over said contact elements and hold them in said retracted position against the bias of said spring and plate and a second position in which said contact elements are free to move to said extended position, releasable means for holding said collar means in said first position, and drag means comprising a plurality of wires attached to said collar means and extending rearwardly of the device, said wires being adapted to contact the interior wall of the pipe to be contacted with said contact elements during movement of said device.

20 4. A device for establishing electrical contact within a pipe which comprises a tubular support member, a plurality of lugs secured to the outside of said support member, said support member having a slot therein adjacent each said lug, a knife-like contact member pivotally secured to each lug having an internal portion extending through the slot adjacent the lug into said support member and a portion external of said support member, said contact members being pivotally mounted for movement between a retracted position in which said external portions extend essentially parallel to the axis of said support member and an extended position in which said external portions extend outwardly from said support member, a plate within said support member resting upon the internal portions of said elements and tending to move 25 said contact elements toward said extended position by gravity when the device is in an upright position, a spring within said support member acting against said plate to bias said contact elements toward said extended position, collar means on said support member movable between a first position in which it is adapted to extend over the external portion of said contact elements and hold them in said retracted position against the bias of said spring and plate and a second position in which said contact elements are free to pivot to said extended position, and releasable means for holding said collar means 30 in said first position comprising spring biased detent means arranged between said collar means and said support member, and drag means comprising a plurality of wires attached to said collar means and extending rearwardly of the device, said wires being adapted to contact the 35 internal wall of the pipe to be contacted with said contact elements during movement of said device.
